Rudolph J. Loz

UNITED STATES PATENT OFFICE.

CHARLES W. KIRSCH, OF STURGIS, MICHIGAN.

CURTAIN FIXTURE.

Application filed November 23, 1922. Serial No. 602,904.

To all whom it may concern:

Be it known that I, CHARLES W. KIRSCH, a citizen of the United States, residing at Sturgis, in the county of St. Joseph and State of Michigan, have invented certain new and useful Improvements in Curtain Fixtures, of which the following is a specification.

This invention relates to improvements in curtain fixtures and more particularly that type of curtain fixture which includes a relatively flat, hollow rod of substantially C-shaped cross section, and brackets for securing the same demountably to a window casing or the like.

The present invention relates more particularly to the means for attaching the rod per se to the wall and has for its object to provide an attaching means whereby the rod is not only securely supported in normal position but whereby it is very firmly held in that position while at the same time it may be very easily and quickly released or detached from the supporting bracket or brackets.

A further object of the invention is to provide attaching means as aforesaid which are so constructed as to permit one end of a curtain rod of any desired length to be first attached to one of its supporting brackets and to be thereby firmly supported in a substantially horizontal position preparatory to attaching the other end thereof to its supporting bracket, this being particularly desirable where the window casings are of extraordinary width and the supporting brackets accordingly widely separated from each other so that it is almost impossible for the person using and attempting to attach and detach such rods from their brackets, to readily attach both ends of the rod simultaneously to the brackets.

The preferred embodiment of the present invention is illustrated in the accompanying drawings wherein:

Figure 1 is a perspective view of a rod and brackets constructed in accordance with the invention, the same being shown as mounted upon a window casing which is shown in fragmentary view; one end of the rod being detached from its bracket.

Fig. 2 is a perspective view of one of the end members of the rod of the type partic-

ularly illustrated in Fig. 1, the middle portion of the rod being adapted to be telescopically engaged with companion members such as is shown in this figure.

Fig. 3 is a detail transverse section taken on the line 3—3 of Fig. 1, the parts being shown in their various positions in part by dotted lines.

Fig. 4 is a detail transverse section on the line 4—4 of Fig. 3, the bracket being shown in front elevation.

Referring now to said drawings, it will be seen that the bracket for supporting the curtain rod comprises a wall plate 1, which may be of any suitable shape such as the oblong shown, from the middle of which a fin-like projection 2 extends outwardly, the latter having a curved or rounded lower front corner 3 and being equipped on its upper edge with a projection 4 having a front rounded face and a rear vertical face, the latter extending from about midway between the front and rear ends or edges of said projection. The said projection 4, in conjunction with the main or body portion of the fin-like flange 2, may be said to constitute a hook. The rod which, in the instance illustrated, consists of a middle portion 5 and two substantially L-shaped end portions 6, all of which are preferably C-shaped in cross section and present a flat outer or front wall, is adapted to be attached to the brackets by means of perforations 7 in the upper flanges of the end or arms of the members 6 which are disposed substantially perpendicularly to the middle portion of the rod, it being preferable to provide a perforation 7 in both the upper and lower flanges contiguous to the ends of said arms so as to render the rod reversible with respect to the brackets. Each of the perforations 7 is spaced from the end of the arm or flange in which it is cut a distance substantially equal to the distance of the vertical face of the hook or projection 4 from the front face of the wall plate 1, said perforation being of a width and length sufficient to receive said projection 4. The depth of the arm of the rod containing said perforations 7 is slightly less than the depth of the main portion of the fin or flange 2 exclusively of the projection 4 so that, in practice, said open end of the arm of the rod is required to be forced upon the fin or flange

100
105

2 by effecting a slight expansion of said open end portion in an obvious manner.

Thus, as is shown in dotted lines in Fig. 3, it is necessary, when attaching the rod 5 to its brackets, to first dispose the arms thereof at about the incline shown in dotted lines in said figure and thereafter turn the same upon the rear face of the projection 4 as a pivot or fulcrum whereby the outer-
10 most portion of the inner face of the lower flange of said arm will be caused to ride upon and be expanded by the curved lower front edge 3 of the fin or flange 2, a portion of the lower face of the latter being prefer-
15 ably flat so that the expansion of the flanges of the rod will be slightly reduced and, in fact, so that they will be brought back to substantially their normal position when said arms have reached the horizontal pos-
20 ition shown in full lines in Fig. 3.

It will be observed that when the said arms are engaged with the brackets, as shown in full lines in Fig. 3, a downward pull on the outer end portion of the arm, or 25 upon the middle portion 5 of the rod, will effect a tension upon the projection 4, will cause the lower edge portion of the end of the arm or arms to bear against the face of the plate 1, thereby maintaining said 30 arms firmly or rigidly in the horizontal position shown and permitting of no sagging whatsoever. The arms of the corner portions 6 of the rod which are engaged with the brackets, are thus so accurately 35 fitted in their abutment against the front face of the plate 1 as to make it appear as though they were a part of said plate.

It will be appreciated that in most instances curtain rods are disposed at the tops 40 of window casings and that the user thereof is generally obliged to employ a chair or ladder in mounting and demounting same for purposes of removing and replacing the curtains or draperies suspended from the rod 45 and that such user, when standing on such supports, is not very safe. Very great ease of attachment and detachment of the rod from its brackets is therefore very advan-
50 tageous, while at the same time a very firm engagement of the rod with the brackets is very desirable. Such firm attachment should, for the sake of safety, be accom-
55 plished with great ease and, likewise, detachment of the rod from the brackets. It 60 will be noted that in the construction as shown the rod is first loosely engaged with the brackets and the pivotal movement necessary to bring it from its upwardly in-
65 clined to its horizontal position, is accom-
plished by a downward pull, either upon the outer end portion of a corner of the rod, or upon the middle portion 5 thereof, the leverage being easily sufficient to over-
come the resistance offered to expansion of 70 the flanges in riding over the rounded lower

front corner portion 3 of the fin or flange 2. It will be further observed that this pull being substantially vertical instead of a force exerted horizontally, is not apt to throw the user off balance when standing on 75 a ladder or other similar relatively unac-
customed support. On the other hand, when it is desired to detach the rod from its brackets, a slight sudden or gradual upward push on the middle portion 5, or contiguous to a 80 corner of the rod, will easily effect a return of the rod to the position shown in dotted lines in Fig. 3, whereupon said rod may be easily disconnected from the brackets.

The firm attachment of the rod to the 85 bracket to prevent any lost motion or rat-
tling, is also very desirable in that, where the window casings are of relatively great width, the user of the rod may set a ladder or other support adjacent one side of the 90 casing and attach one of the arms of the rod to the bracket, bringing it to the horizontal position shown in Fig. 3, without at the same time engaging the other end of the 95 rod with its companion bracket. The snug fit will support the rod in a substantially horizontal position without any great amount of sagging, the latter depending, of course, upon the weight of the curtains or 100 draperies, the tendency being for the weight generally speaking, no permanent distortion will take place because of the flexibility of the metal of which the rod is best adapted to be made. The user may then set the ladder, or the like, adjacent the other side of the 105 window casing and then effect attachment of the other arm of the rod to its companion bracket, and can generally accomplish this without causing the first attached arm to 110 leave its horizontal position owing to the flexibility of the metal and the very slight torsional strain necessary to bring the sec-
ond arm to the position shown in dotted lines in Fig. 3 preparatory to bringing it back to its horizontal position.

A further advantage resulting from the firm attachment aforesaid is that, at times, it may happen that a child will give a sudden jerk on the curtain or drapery or suddenly release the same after a downward pull thereon, with the result that the middle portion of the rod will be somewhat flexed, and in suddenly springing back to its normal position it is possible that, in the absence of a very snug fit between the rod and its brackets, the said rod may spring upwardly to an extent to cause one or both ends thereof to become detached from the bracket, whereas a snug fit, such as is herein illustrated and described, will prevent 125 such action.

While I have shown the preferred em-
bodyment of the invention in the accom-
panying drawings, it will be obvious, of 130 course, that such embodiment is capable of

change and variation to some extent without departing from the invention as defined in the appended claims.

I claim as my invention:

- 5 1. A curtain fixture comprising a hollow rod open at its ends, and a pair of supporting brackets adapted to be mounted on a window casing, the middle portion of said rod extending substantially perpendicularly to the end portions thereof and said end- 70
10 portions adapted to extend substantially horizontally outwardly from said brackets, the latter including elements adapted to project into the ends of the rod, said rod and said elements including inter-engaging formations for preventing movement of said end-portions of said rod away from said brackets in any direction except upwardly and permitting a limited pivotal movement 75
15 of the end-portions of the rod relatively to the brackets without effecting disengagement of the rod from the brackets, whereby said rod may be initially engaged with said brackets by disposing the end-portions of 80
20 said rod at an upward incline relatively to said brackets and subsequently swung to horizontal position, said elements including means adapted to yieldably engage the said end-portions of the rod as the latter are 85
25 swung to horizontal position for resisting upward swing of said end-portions preparatory to effecting disengagement of said rod 90
30 from said brackets. 95
2. A curtain fixture including a rod having end-portions adapted to extend substantially horizontally outwardly from a window casing or the like, and a pair of brackets for supporting said rod, the latter and the extreme ends of said rod including inter-engaging formations for effecting attachment of the rod to the brackets at points above the middle of the ends of said rod for preventing disengaging movement of said rod relatively to said brackets in any direction except one and further including parts on said brackets below the level of said inter-engaging formations against which the ends of said rod abut when the said end-portions thereof extend substantially 100
40 horizontally and coacting with said inter-engaging formations to rigidly support said end-portions of said rod in said position, said inter-engaging formations permitting and requiring pivotal movement of said end- 105
45 portions of said rod upwardly from horizontal position preparatory to effecting disengagement or inter-engagement of said formations, and inter-engaging means on the rod and brackets disposed below the said 110
50 formations for yieldably resisting swing of said end-portions of said rod to and from said horizontal position while said formations are inter-engaged, whereby said end- 115
55 portions are firmly held in said horizontal position while permitting said rod and 120
60 formations for yieldably resisting swing of said end-portions of said rod to and from said horizontal position while said formations are inter-engaged, whereby said end- 125
65 portions are firmly held in said horizontal position while permitting said rod and 130
- brackets to be readily dissociated and associated when desired.
3. A curtain fixture comprising a rod having a middle portion adapted to extend substantially parallel with a window casing or the like, and two end-portions extending substantially perpendicularly to said middle portion, said end-portions hollow and open at their free ends, a pair of supporting brackets adapted to be secured to the window-casing, the said brackets and free ends of the rod equipped with inter-engaging formations disposed at substantially the highest point in each for effecting attachment of the rod with said brackets, the latter presenting parts below the level of said formations against which the free ends of the rod abut and coact with said formations to support said end-portions of said rod in horizontal position, said rod and brackets equipped with yielding inter-engaging means below said formations coacting to firmly hold the end-portions of the rod against free movement relatively to the bracket in any direction and permitting engagement of one free end of the rod with one of said brackets while the other free end remains disengaged from its bracket and supporting the middle portion of the rod in substantially horizontal position preparatory to effecting engagement of said other free end with its bracket.
4. A curtain fixture comprising a flat rod of substantially C-shaped cross-section and having arms extending substantially perpendicularly to its main or middle portion, the latter adapted to be horizontally disposed substantially parallel with the plane of a window casing, there being perforations in the outermost portions of the flanges of said rods contiguous to the free ends of the arms thereof, a pair of brackets for supporting said rod comprising wall plates adapted to be secured to the window casing, projections on said wall plates including hooks adapted to engage in the perforations in the upper flanges of the rod and parts adapted to yieldably engage in the channels of the lower flanges of the rod at the free ends of said arms for resisting free movement of the rod relatively to said brackets, the free ends of said arms adapted to abut against the said wall plates, the latter coacting with said hooks to maintain said arms horizontally disposed, and each of said parts engaging in the channels of the lower flanges adapted to coact with its companion hook, when only one of the latter is engaged with an arm of the rod, to maintain the middle or main portion of the rod substantially horizontally disposed preparatory to effecting engagement of the other arm of the rod with its bracket.
5. A curtain fixture comprising a substantially V-shaped rod adapted to be supported

so that its middle and end-portions are horizontally disposed, said end-portions of said rod being hollow and open at their ends and presenting opposed flexible top and bottom wall portions, a pair of brackets including projections of greater depth between their uppermost and lowermost edge-portions than the distance between the opposed wall portions of the end-portions of 5 the rod and being adapted to be forced to enter said open ends of the rod by flexion of said wall portions thereof, the upper-most wall-portions and edge-portions of said projections of said flanges equipped with inter-engaging formations for preventing movement of the rod outwardly from the brackets when the said rod is horizontally disposed, said rod adapted to be tilted at an upward incline relatively to the brackets 10 for effecting initial inter-engagement of said formations as said rod is forcibly swung downwardly to horizontal position to cause the lowermost edge-portions of the said projections to engage the inner surface of the 15 lowermost wall-portions of the rod.

6. A curtain fixture comprising a pair of supports adapted to be fixed to a window casing or the like, each thereof including a flange equipped at substantially the meeting 20 point of its front and top edges with an upwardly extending projection, the lower front corner of said flange being cut away, a curtain rod having parallel hollow arms presenting opposed flexible top and bottom 25 wall portions separated from each other a distance less than the height of said flange, there being perforations in the upper wall portions adjacent the ends of said arms to receive said projections, said rod adapted 30 to be engaged with said flanges by primarily tilting said arms and effecting engagement of said projections in said perforations and then bringing said arms to a horizontal 35 position, the edges of the lower wall portions being primarily in contact with said cut away portions of said flanges and being 40

flexed as forcible entry of the flanges into the ends of said arms is effected as the latter are moved to horizontal position, whereby a clamp-like engagement between the rod 50 and said supports is effected.

7. A curtain fixture comprising a hollow rod presenting opposed flexible wall portions adapted to be engaged at their extremities with supporting devices, and supporting devices adapted to be mounted on a window casing or the like, said supporting devices and one of said flexible wall portions of said rod equipped with inter-engaging formations for preventing movement of the rod 55 away from said devices while permitting a limited swinging movement of the rod from a horizontal position to an upward incline and vice versa, there being a cam element associated with the said formations of each support for engaging and flexing the other of said wall portions of said rod as the latter is swung from its upward incline to horizontal position and coacting with said formations to hold said rod firmly and yieldably engaged with said supports.

8. A curtain fixture comprising a hollow rod of substantially C-shaped cross-section, the opposed flanges thereof being flexible, a supporting device for said rod comprising a wall fixture presenting a hook, there being a perforation in the upper flange of the rod to receive said hook, said wall fixture further presenting a cam surfaced portion below the hook against a part of which the end of the lower flange of the rod is adapted to abut when said hook is engaged in said perforation for normally holding said rod to extend at an upward incline relatively to said wall fixture, said rod adapted to be forcibly swung downwardly on said hook as a pivot to cause said cam surfaced portion to forcibly enter the end of the rod, whereby said flanges are flexed and obtain a firm yielding hold on 80 said wall fixtures.

CHARLES W. KIRSCH.
